DISPLAY SIGN

Joseph N. Klema, Austin, Minn.

Application October 10, 1935, Serial No. 44,435

8 Claims. (Cl. 40—30)

This invention relates to a display sign and has relation more particularly to a sign of a changeable exhibitor type, and it is primarily an object of the invention to provide a sign with relatively 5 movable members, said members making different displays when adjusted into different assemblies.

It is also an object of the invention to provide a sign of this kind comprising stationary paddles and movable paddles, the movable paddles when 10 in one position coacting with the stationary paddles to complete one display and said movable paddles when in a second position coacting with each other to provide another display.

Another object of the invention is to provide a 15 device of this kind comprising a plurality of paddles certain of which being fixedly mounted and the others mounted for movement with respect to the first named paddles and to each other and wherein the mounting for each of the 20 paddles is such to permit the same to be readily removed when desired so that different combinations of paddles may be employed as the character of the display may necessitate.

The invention consists in the details of construction and in the combination and arrangement of the several parts of my improved display sign whereby certain important advantages are attained and the device rendered simpler, less expensive and otherwise more convenient and 25 advantageous for use, as will be hereinafter more fully set forth.

The novel features of my invention will hereinafter be definitely claimed.

In order that my invention may be the better 35 understood, I will now proceed to describe the same with reference to the accompanying drawings, wherein:—

Figure 1 is a view in elevation of a sign constructed in accordance with an embodiment of 40 my invention;

Figure 2 is a view in rear elevation of the structure as illustrated in Figure 1;

Figure 3 is a view similar to Figure 1 but illustrating certain of the paddles in a second position;

Figure 4 is a view in top plan of the device as illustrated in Figure 3;

Figure 5 is a view in end elevation of a pair 50 of associated paddles illustrating in detail the manner herein disclosed whereby one paddle interlocks with the other;

Figure 6 is a fragmentary elevational view illustrating a paddle constructed in accordance 55 with another embodiment of my invention;

Figure 7 is a view in front elevation of a sign constructed in accordance with another embodiment;

Figure 8 is a view in rear elevation of the structure as illustrated in Figure 7;

Figure 9 is a sectional view taken substantially on the line 9—9 of Figure 7.

As illustrated in Figures 1 to 5, the sign comprises a base 1 of suitable dimensions and which is adapted to be mounted or placed as desired. 5 One end portion of the base carries an upstanding plate 2 and mounted, as at 3, upon the base 1 to the rear of the plate 2 is a worm wheel 4. Meshing with this worm wheel 4 is a worm 5 driven by the motor M, preferably of an electrical 10 type.

The lower portion of the plate 2 has disposed transversely thereacross and extending beyond opposite sides thereof an elongated strip 6 upon which is adapted to be arranged a suitable display 7, such display as herein illustrated constituting the words "On sale". The plate 2 has secured to its rear face at opposite sides thereof the outwardly opening socket members 8 and 9. These socket members are arranged in pairs in 20 substantially transverse alignment with the socket members 8 lowermost. The axes of the socket members 8, as is clearly illustrated in Figure 2 of the drawings, are angularly disposed with respect to the longitudinal axes of the socket 25 members 9. Each of these socket members 9 is adapted to receive the offset shanks 10 of the elongated paddles 11. The offset 12 of each of the paddles 11 operatively engaged with a lower socket member 8 is of an extent to position the 30 paddle 11 in advance of the plate 2 and in the path of travel of one of the lower swinging paddles 15 so that when said paddle 15 is in its lowered position it will closely approach the lower paddle 11 so that the displays carried by the outer faces 35 of said paddles 11 and 15 will combine or harmonize to produce a readily discernible display.

When the lower swinging paddles 15 are at the limit of their upward swinging movement they are substantially vertically disposed with 40 adjacent margins in close contact and when in such position display matter lower carried by the outer faces of these paddles 15 combine or harmonize to afford a second discernible display. In other words, when each of the paddles 15 45 is in its lowermost position it combines with a lower lateral paddle 11 to provide what may be termed a panel for one display and when the swinging paddles 15 are in their uppermost or vertical position they provide what may be 50 termed a second panel for another display. However, no one of the paddles carries a complete display but must of necessity co-operate with a second paddle for such complete display.

The inner end portion of each of the paddles 55 15 is extended by a shank 16 as indicated by broken lines in Figure 1 for insertion within an outwardly opening socket member 17. This member 17 has its outer corner at its closed or inner end fixed to a shaft 18 for rocking movement 60

with said shaft. This shaft is rotatably disposed through and supported by the plate 2. The offset 12 connecting the shank 10 with an upper paddle 11 is of an extent to position said applied upper paddle 11 in advance of the plate 2 but inwardly of and out of the path of travel of the paddles 15 but within the path of travel of the upper swinging paddles 19. Each of these paddles 19 when in its lowered position registers with an upper side paddle 11 and when at the limit of its upward movement is in close contact with the second upper paddle 19 and in a vertically disposed position. The outer faces of the paddles 15 and 19 are provided with display matter properly combining or harmonizing when the paddles 19 are in lowered position, and said paddles 19 are also provided with additional matter properly combining or harmonizing when said paddles 19 are at the limit of their upward movement.

20 The paddles 19 are also provided at their inner ends with the shanks 20 as indicated by broken lines in Figure 1 which are received within the socket members 21, the outer corners of which at the inner or closed ends thereof being fixed to and rocking with the shafts 22. These shafts 22 are also disposed through and supported by the plate 2 and each of these shafts 22 is positioned a desired distance above and substantially in vertical alignment with a shaft 18 hereinbefore referred to.

The portions of the shafts 18 and 22 extending beyond the rear face of the plate 2 are operatively connected for unitary rocking movement and for which purpose, as illustrated in Figure 2, the rear portions of the shafts 18 are provided with the upstanding rock arms 23 connected by the links 24 with the bell crank levers 25 fixed to the rear portions of the shafts 22. The bell crank levers 25 have inner arms connected by the links 26 with a rock arm 27 supported by the plate 2 as are also the bell crank levers 25. This rock arm 27, as illustrated in Figure 2, has operatively engaged therewith a rod 28 which is eccentrically connected, as at 45 29, with the worm wheel 4 hereinbefore referred to.

As the wheel 4 rotates the paddles 15 and 19 will be caused to oscillate and at a frequency determined by the speed of rotation of the worm wheel 4. The paddles 15 and 19 reach their limits of swinging movement in either direction a time before the pivotal connection 29 reaches a vertical center so that during the period required for the connection 29 to pass beyond 55 such vertical center the paddles 15 and 19 will be maintained stationary and thus assuring an effective display.

While the accompanying drawings disclose a particular system of levers for operating the paddles 15 and 19, it is to be understood that it is within the scope of the invention to provide a combination of levers other than that illustrated and herein described and I, therefore, wish to particularly state at this time that the exact means for effecting the oscillation of the paddles 15 and 19 and more particularly their associated socket members 8 and 9 forms no particular part of the present invention.

As illustrated in Figures 1 and 3 the display matter on the paddles 11, 15 and 19 pertains to merchandise generally found on sale in grocery stores or the like but I do not wish to be understood as limiting myself to this particular character of display or to the particular words 75 illustrated by the drawings.

As illustrated in Figures 1 and 3, the outer end portions of the paddles 19 carry the laterally directed extension plates 30 upon which any suitable matter may be produced. For example, should the paddles 19 when in their vertical position have a combination identifying an oil company, these extension plates 30 may have produced thereon the words "Oil" and/or "Gas". The uses to which my improved sign may be put are many and as for a further example, I 10 wish to say that it can also be constructed for use at railroad crossings and when so used as illustrated in Figure 6, each of the paddles 31, either movable or immovable, in addition to the desired display or warning will carry an illuminating unit 32 such as an electric bulb so that the sign or signal will be readily observed after nightfall.

Figure 5 is a view in plan illustrating the outer ends of the paddles 15 and each of the paddles 20 11 is also formed in the same manner as each of these paddles 15. As disclosed in this Figure 5, one longitudinal margin of the paddle 15 is formed to provide an elongated socket 33 and having its opposite longitudinal marginal portion provided therealong with an offset flange or tongue 34. When the paddles 15 are in their fully raised position, as illustrated in Figure 3, the flange or tongue 34 of one paddle will be received within the longitudinal socket 33 of the second paddle as 30 clearly illustrated in Figure 5, thus assuring the complementary paddles being maintained in a fixed position one with respect to the other for enhancing the desired display. Such an arrangement is equally true with respect to the oscillating paddles 19. The paddles 11 along their marginal portions are each formed to provide a longitudinally disposed socket similar to the socket 33 to receive the tongue or flange 34 of a paddle 15 or 19 when such oscillating paddle is 40 at the limit of its movement toward a stationary paddle.

In the embodiment of the invention as illustrated in Figures 7 and 8, the upstanding plate 2' has extending thereacross for a desired distance beyond opposite sides thereof an elongated strip or plate 35, the upper marginal portion of which being defined by an upstanding flange or tongue 36 which provides a runway for a slide plate or elongated member 37. The lower marginal portion of this plate or member 37 has extending therealong a socket 38 which receives the tongue or flange 36 whereby the plate or member 37 is permitted to have reciprocating movement in a fixed path of travel. The plate or member 37 is of a length materially less than the plate or member 35 and the opposite end portions of this member or plate 35 carry the upstanding paddles 39. The extremities of the member or plate 35 are also provided with the upstanding paddles 40 and adjacent paddles 39 and 40 are provided on their outer faces with suitable matter which, when a pair of paddles 39 and 40 are substantially in contact, provides a desired display. As is believed to be clearly understood from Figures 7 and 8 of the drawings, when one pair of paddles 39 and 40 are substantially in contact to effect a display the pair of paddles 39 and 40 at the opposite ends of the plates or members 35 70 and 37 are separated.

The outer faces of the members or plates 37 in central portions thereof are provided with suitable matter which, when a member or plate 37 is at the limit of its movement in one direction, 75

combine or harmonize to provide a desired display.

5 Mounted upon the base plate or member 1' is a motor M' positioned rearwardly of the plate 2' and which motor is also preferably of an electrical type. This motor M' operates a worm 5' which meshes with a worm wheel 4'. This worm wheel has operatively connected thereto an end portion of a rod or pitman 28', the opposite end 10 portion of which being operatively connected to an end portion of the member or plate 37. As the worm wheel 4' rotates the member or plate 37 will be caused to reciprocate whereby the desired displays are alternately produced in time 15 sequence at the opposite end portions of the member or plate 37.

20 While the accompanying drawings particularly illustrate a worm and gear drive, it is to be understood that other means may be employed with equal facility to effect the desired operation of the paddles. For example, the gear 4 may be in the nature of a disk mounted directly upon the drive shaft of the motor or I can employ substantially the same driving means as illustrated 25 in my Patent 2,012,468 which issued August 27, 1935.

30 From the foregoing description it is thought to be obvious that a display sign constructed in accordance with my invention is particularly well adapted for use by reason of the convenience and facility with which it may be assembled and operated, and it will also be obvious that my invention is susceptible of some change and modification without departing from the principles 35 and spirit thereof and for this reason I do not wish to be understood as limiting myself to the precise arrangement and formation of the several parts herein shown in carrying out my invention in practice except as hereinafter claimed.

40 I claim:—

1. A sign of the class described comprising paddles, means for supporting said paddles in fixed positions, movable paddles supported for movement toward and from the fixed paddles, 45 complementary faces of the paddles carrying matter combining to provide a display when the movable paddles are at their limit of movement toward the fixed paddles.

2. A sign of the class described comprising paddles, means for supporting said paddles in fixed 50 positions, movable paddles supported for movement toward and from the fixed paddles, complementary faces of the paddles carrying matter combining to provide a display when the movable paddles are at their limit of movement toward the fixed paddles and when the movable paddles 55 are at their limit of movement toward each other.

3. A sign of the class described comprising a fixed paddle, a movable paddle, means for supporting said movable paddle for movement toward or from the fixed paddle, means for intermittently moving the movable paddle toward and from the fixed paddle, complementary faces of the 60 fixed paddle and movable paddle having matter combining to provide a display when said paddles are at the limit of their movements one toward the other.

4. A display sign comprising an upstanding plate, paddles carried by and extending beyond 65 opposite sides of the plate, paddles pivotally connected to the plate and also extending beyond opposite sides thereof, and means for swinging the second paddles into close contact with the first named paddles and also moving said second 70 paddles in the opposite direction to bring said

movable paddles into close contact, the outer faces of the first named paddles and the swinging paddles having matter thereon combining to produce a display when the movable paddles are in close contact with the first named paddles and also to provide display when the movable paddles are in close contact one with the other. 5

5. A display sign comprising an upstanding plate, paddles carried by and extending beyond opposite sides of the plate, paddles pivotally connected to the plate and also extending beyond opposite sides thereof, and means for swinging the second paddles into close contact with the first named paddles and also moving said second paddles in the opposite direction to bring said 15 movable paddles into close contact, the outer faces of the first named paddles and the swinging paddles having matter thereon combining to produce a display when the movable paddles are in close contact with the first named paddles and 20 also to provide display when the movable paddles are in close contact one with the other, said paddles when in close contact one with the other being substantially vertically disposed.

6. A display sign comprising an upstanding 25 plate, paddles carried by and extending beyond opposite sides of the plate, paddles pivotally connected to the plate and also extending beyond opposite sides thereof, and means for swinging the second paddles into close contact with the 30 first named paddles and also moving said second paddles in the opposite direction to bring said movable paddles into close contact, the outer faces of the first named paddles and the swinging paddles having matter thereon combining to 35 produce a display when the movable paddles are in close contact with the first named paddles and also to provide display when the movable paddles are in close contact one with the other, the first named paddles and the second named paddles 40 having means interlocking when the second paddles are in close contact with the first named paddles.

7. A display sign comprising an upstanding plate, paddles carried by and extending beyond 45 opposite sides of the plate, paddles pivotally connected to the plate and also extending beyond opposite sides thereof, and means for swinging the second paddles into close contact with the first named paddles and also moving said second 50 paddles in the opposite direction to bring said movable paddles into close contact, the outer faces of the first named paddles and the swinging paddles having matter thereon combining to produce a display when the movable paddles 55 are in close contact with the first named paddles and also to provide display when the movable paddles are in close contact one with the other, the first named paddles and the second named paddles having means interlocking when the second 60 paddles are in close contact with the first named paddles, said second paddles also having means interlocking when said second paddles are in close contact one with the other. 65

8. A sign of the class described comprising paddles, means for supporting said paddles in fixed positions, movable paddles supported for movement toward and from the fixed paddles, complementary faces of the paddles carrying matter combining to provide a display when the movable paddles are at their limit of movement toward the fixed paddles, and an illuminating unit 70 carried by a paddle. 75
